Filed Jan. 10, 1969, Ser. No. 15,310

Term of patent 14 years

Int. Cl. D10—08

U.S. Cl. D52—6

FIG. 1

FIG. 2

FIG. 3

FIG. 1 is a perspective view of a punch card counting device showing my new design;

FIG. 2 is a top plan view of the punch card counting device shown in FIG. 1;

FIG. 3 is a side elevational view of the punch card counting device shown in FIGS. 1 and 2.

The characteristic features of my new design reside in the specific shape of the slider and in the flush upper surfaces of the slider, the scale, and the end piece as shown.

I claim:

The ornamental design for a punch card counting device, as shown and described.
